(57) **CLAIM**

The ornamental design for a device for radio frequency ablation, as shown and described.

DESCRIPTION

FIG. 1 is a front, right-side, top perspective view of a device for radio frequency ablation showing our new design; FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front, right-side, top perspective view thereof, with the display panel flipped downwards;

FIG. 9 is a front view thereof, with the display panel flipped downwards;

FIG. 10 is a back view thereof, with the display panel flipped downwards;

FIG. 11 is a left-side view thereof, with the display panel flipped downwards;

FIG. 12 is a right-side view thereof, with the display panel flipped downwards;

FIG. 13 is a top view thereof, with the display panel flipped downwards; and,

FIG. 14 is a bottom view thereof, with the display panel flipped downwards.

The equal length broken lines in the drawings depict portions of the device for radio frequency ablation that form no part of the claimed design.
